UNITED STATES PATENT OFFICE.

GEORGE W. GARNISSL, OF YARMOUTHVILLE, MAINE.

CABINET.

1,409,942.

Specification of Letters Patent. Patented Mar. 21, 1922.

Application filed October 21, 1920. Serial No. 418,495.

To all whom it may concern:

Be it known that I, GEORGE W. GARNISSL, a citizen of the United States, residing at Yarmouthville, in the county of Cumberland and State of Maine, have invented certain new and useful Improvements in Cabinets, of which the following is a specification.

My invention consists in a new and useful improvement in cabinets, and is designed to afford a cabinet provided with bathing means in combination with a dressing table and receptacles and racks suitable for containing and displaying any and all articles requisite to bathing and dressing. It is more particularly designed for use in bathing and dressing infants and an especial feature of its utility consists in the fact that the relation of the various parts may be altered by the use of one hand only, allowing the attendant to support the infant in one hand and secure the necessary arrangement of the parts with the other hand. The various parts are designed to be so related and proportioned that they are readily accessible to the user, and may be utilized with the minimum of effort. A particularly important feature of the relation and proportion of the parts is that their use does not compel the user to bend or stoop, an advantage of paramount value in the case of use of the cabinet by the mother of an infant. When the parts are arranged for the purpose of dressing an infant, the dressing table is adapted to be equipped with a novel form of safety belt suitable for securing the infant upon the table with ample comfort and safety, while allowing a moderate freedom of movement. Another valuable feature of the invention is the sanitary character of the parts and their arrangement affording opportunity for removal of the bathing means and thorough cleaning of all parts liable to become soiled in the use of the cabinet.

The invention is embodied in the details of construction illustrated in the drawings and hereinafter fully described, but I do not consider my invention limited to the specific embodiment herein set forth and refer for its scope to the claims appended hereto.

50 In the drawings:

Fig. 1 is a perspective view of a cabinet embodying the invention indicating the parts in normal position when the cabinet is not in use.

55 Fig. 2 is a view similar to Fig. 1 indicat-

ing the parts in position for use of the cabinet for bathing purposes.

Fig. 3 is a perspective view of a portion of the cabinet indicating the parts in position for use of the cabinet for dressing purposes.

Fig. 4 is a vertical sectional view of the device.

In the drawings:

The numeral 1 designates an improved cabinet embodying my invention, provided with the end walls 1^a, 1^b and the bottom 1^c and top 1^d, extending between said end walls. Between the top 1^d and bottom 1^c at a point slightly to the rear of the vertical median line of the ends extends between the ends the partition 1^e. The foregoing structure provides a receptacle 2 at the front of the cabinet, and a receptacle 3 at the rear. Located in the top 1^d and substantially equal to the surface area of the receptacle 2 is the removable cover 2^a. The front of the receptacle 2 is provided with a door 2^b hinged at its lower edge by hinges 2^c to the bottom 1^c. Both the cover 2^a and door 2^b may be provided with pull rings 2^d and 2^e respectively to facilitate the removal of the cover 2^a and opening of the door 2^b. A mat M of rubber or any suitable material may be placed upon the bottom 1^c within the receptacle 2, and upon this mat M may be placed a bath tub T or any suitable bathing utensil.

The cabinet is mounted upon legs 1^f, and is provided with a shelf 1^g below the bottom 1^c and extending between the legs 1^f.

Depending from the bottom 1^c are hangers 1^h and pins 1ⁱ extending from the two front legs 1^f to support the cover 2^a, which may thus be readily disposed of when removed from the receptacle.

The receptacle 3 is provided with a door 3^a mounted on hinges 3^b upon the bottom 1^c. This door may also be provided with a pull ring such as the one upon the door 2^b.

Within the receptacle 3, the end walls 1^a and 1^b are provided with cleats 3^c upon which is mounted a spring roller 4, such as is used for window shades. Upon this roller 4 is mounted a flexible sheet 5 of canvas, sanitary webbing or any similar suitable material. The outer edge of this sheet 5 is threaded through a slot 1^d in the top 1^d located above and slightly in front of the roller 4. The outer edge of the sheet 5 is provided with a wide hem 5^a adapted to encase therein a

rigid rod 5^b having flattened ends 5^c extending beyond the ends of the edge of the sheet 5. Located at the front end upon the top of the end walls 1^a and 1^b are the clips 5^d adapted to receive therein the flattened ends 5^c of the rod 5^b. The sheet 5 is provided upon its sides with the loops 5^e which are adapted to pass over the upper edges of the end walls 1^a and 1^b and be received upon the knobs 5^g thereon. When the sheet 5 is drawn from the roller 4 and stretched above the receptacle 2 by the functioning of the rod 5^b, clips 5^d and loops 5^e, a pad P may be placed upon the sheet 5.

15 Located upon the top 1^d above the receptacle 3 are a series of receptacles formed by the rear wall 6 located immediately above the door 3^a and the front walls 6^a, both extending between the upwardly extending projections 1^{a'} and 1^{b'} of the end walls 1^a and 1^b. Between the walls 6 and 6^a, a division wall 6^b forms a large receptacle adjacent the end wall 1^b and several division walls 6^c form a number of receptacles through the remaining width of the cabinet. The large receptacle has a separate cover 6^d and the other receptacles have a common cover 6^e. The covers 6^d and 6^e are hinged to the rear wall 6 by the hinges 6^f, and are provided with knobs 6^g to facilitate opening.

Upon the outside of the end walls 1^a and 1^b near the top 1^d are located at front and rear blocks 1^{a''} and 1^{b''} respectively. Journaled in the blocks 1^{a''} is a rod 7 upon each end of which is mounted a bar 7^a. These bars 7^a are connected by rods 7^b, any desired number being provided. A similar construction is mounted in the blocks 1^{b''}. This construction provides a rack upon each end of the cabinet. The rods 7 are provided at their ends with threaded portions 7^c upon which are carried wing nuts 7^d, permitting tension to be put upon the rods 7 by binding the wing nuts against the blocks 1^{a''} and 1^{b''}, thus permitting adjustment of the bars 7^a at any angle relative to the cabinet, and allowing the racks to be disposed as desired.

50 In the center of the outer face of the wall 6^a, there is provided a screw-eye 6^{a'} to which the improved safety belt 8 may be attached by means of the snap-hook 8^a. The reference character I designates the figure of an infant to whom the belt 8 is applied. As shown, the belt is designed to encircle the body approximately at the waist line. Two straps 8^b and 8^c of muslin, webbing or any suitable material are provided with loops 8^{b'} and 8^{c'} respectively at one end of each strap through which the belt 8 passes at the back of the infant I. The strap 8^b has a loop 8^d through which the strap 8^c passes at a point approximately in the small of the back of the infant. The two straps 8^b and

8^c thus crossed under the infant's back, pass over his shoulders and are again crossed over his breast, strap 8^e passing through loop 8^e in the strap 8^b. Both straps 8^b and 8^c are provided with several loops 8^f through which passes the belt 8, passing around the front of the waist of the infant. Providing several loops 8^f in each strap 8^b and 8^c permits adjustment of the belt 8 in accordance with the size of the infant. A strap 8^g has at one end a ring 8^h through which the belt 8 is passed, and the strap 8^g is provided with a snap hook 8ⁱ which is fastened in the ring 8^h attached to the rod 5^b and extending through the hem 5^a of the sheet 5.

80

The foregoing description regarding the safety belt indicates its use when the infant is placed upon the pad P upon the sheet 5.

If it is desired to use the safety belt when the infant is in the tub T, the snap-hook 8^a is fastened in the screw-eye 6^{a''} located in the edge of the top 1^d at the rear of the opening formed by the removal of the top 1^d at the rear of the opening formed by the removal of the cover 2^b of the receptacle 2 and the snap-hook 8ⁱ is fastened in the screw eye 5^e; located in the edge of the top 1^d at the front of the opening.

85

The relation of the parts of the safety belt 8 and the straps 8^b and 8^c is such that when it is adjusted upon the infant in the tub, it is not possible for the infant to lie down.

90

From the foregoing description, the use and operation of the device embodying my invention will be obvious. As the device is of particular value in the care of infants, its use for such purpose will be described, but it will be understood that its use is by no means limited to use for the care of infants.

100

The parts being in the position indicated in Fig. 1, the cover 2^a is removed and placed beneath the bottom 1^c resting upon the hangers 1^b and 1^{b'}. The door 2^b being opened and swung downwardly, the receptacle 2 is now open and ready to receive the mat M and the bath tub T, which may be filled with water either before it is placed in the receptacle 2, or by pouring the water into the tub through the top opening afforded by the removal of the cover 2^a. The parts are now in the position indicated in Fig 2, and the cabinet is ready for bathing the infant. During the bath, should the mother or attendant be called away, and it is not desired to remove the infant from the tub T, the safety belt may be applied as indicated in Fig. 2, preventing the infant from getting out of the tub or lying down in the tub, while unattended.

110

After the bathing has been completed, the racks at the sides of the device may be adjusted and the wash rags, towels and articles of clothing disposed thereon as desired.

120

The infant may be taken from the bath tub

130

T and held in the left arm of the mother or attendant, and the sheet 5 put in place to afford a dressing table. This may be done by using the right hand only, thus obviating the necessity for laying the infant down during the adjustment of the dressing table. Taking hold of the screw-eye 5^e, the mother or attendant may draw the sheet 5 upwardly its full length. The sheet 5 is then lowered over the open top of the receptacle 2 and the flattened end 5^e of the rod 5^b at the left-hand side is slipped into its corresponding clip 5^d. The hand can then be slid along the rod 5^b to the right-hand end and the flattened end 5^e at that end, adjusted in its corresponding clip 5^d. The loops 5^f may then be placed over the knobs 5^g and the sheet 5 is properly stretched to form the dressing table, and a pad P may be placed thereon, upon which the infant may be laid.

Through the opening afforded by the door 2^b, the bath tub T may be removed from the receptacle 2 without disturbing the infant upon the dressing table.

25 The receptacles at the rear of the dressing table afford repositories for toilet and medical accessories of the bath, and infant dressing, such as safety pins, powder, cold cream, medical bandages, etc. Owing to the location of these receptacles, the articles contained therein are readily accessible to the mother or attendant while bathing and dressing the infant.

If it is desired to leave the infant upon the dressing table, the safety belt may be adjusted as indicated in Fig. 4.

Having described my invention, what I claim is:

1. The combination in a toilet stand of 40 bathing means; and means adapted to provide a dressing table comprising a flexible member adapted to be normally received in said stand and to be stretched above said bathing means and provided with fastening 45 means adapted to maintain said member in stretched position, said fastening means being also adapted to be engaged and disengaged by the use of one hand of the user of said device.

50 2. The combination in a cabinet of bathing means; and means adapted to provide a dressing table adapted to be located above said bathing means, comprising a flexible sheet provided with an inflexible rod at one end, and provided further with loops, said cabinet being provided with clips adapted to receive said rod therein, and provided also with knobs adapted to receive said loops, said rod, clips, loops and knobs being adapted to retain said sheet in position to provide a dressing table.

3. The combination in a cabinet of bathing means; and means adapted to provide a

dressing table adapted to be located above said bathing means, comprising a flexible sheet provided with an inflexible rod at one end, said rod having flattened ends, and provided further with loops, said cabinet being provided with clips adapted to receive said flattened ends, and provided also with knobs adapted to receive said loops, said rod, clips, loops and knobs being adapted to retain said sheet in position to provide a dressing table.

4. In a toilet stand, the combination of a receptacle adapted to receive a bath tub; a removable top for said receptacle; a second receptacle; a spring roller mounted in said second mentioned receptacle, a flexible sheet adapted to be normally coiled upon said roller and further adapted to be drawn from said roller and stretched above said first mentioned receptacle to form a cover for same when said top is removed.

5. In a toilet stand, the combination of a receptacle adapted to receive a bath tub; a flexible sheet adapted to be stretched above said receptacle; and an opening in said receptacle adapted to permit the insertion into and withdrawal from said receptacle of said bath tub when said sheet is stretched above said receptacle.

6. In a device of the character specified, the combination of a receptacle adapted to receive a bath tub; a flexible sheet adapted to be stretched above said receptacle; and a hinged door to said receptacle, adapted to permit the insertion into and withdrawal from said receptacle of said bath tub when said sheet is stretched above said receptacle.

7. In a toilet stand, the combination of a receptacle adapted to receive a bath tub and provided with an opening in its top; a flexible sheet mounted upon a roller adjacent said receptacle and adapted to be stretched across said opening; and a hinged door to 105 said receptacle adapted to permit the insertion into and withdrawal from said receptacle of said bath tub when said sheet is stretched across said opening.

8. In a device of the character specified, 110 the combination of a receptacle adapted to receive a bath tub; a second receptacle adjacent said first receptacle; a roller mounted in said second receptacle and adapted to be removed therefrom; a flexible sheet mounted upon said roller and adapted to be stretched to form a cover for said first mentioned receptacle; and a hinged door applied to each of said receptacles, the door of said first mentioned receptacle being adapted to permit the insertion into and the withdrawal from said receptacle of said bath tub when said sheet is stretched.

In testimony whereof I affix my signature.

GEORGE W. GARNISSL
